WATER BAG

Mae H. Brown, Polk, Mo.

Application October 6, 1937, Serial No. 167,622

6 Claims. (Cl. 128—258)

The present invention relates to water bags and more particularly to improvements in the construction and uses of a liquid container of this type.

5 In the use of water bags, it is essential for the cooling or heating liquid to be uniformly applied to the part of the body being treated. If the liquid is allowed to escape from the affected part, its efficiency will be seriously impaired. Accordingly, an important feature of 10 the present invention is to provide a liquid receptacle such as a hot or cold water bag, with means in the form of separate compartments for receiving and retaining or localizing the liquid therein irrespective of the different shapes the bag may assume or the varying pressures to which it may be subjected when in use.

A further object consists in providing the bag with an inlet or filling passage in the form of 20 a tubular member for conducting the liquid to the compartments, and associating with the tubular member a removable closure for cutting off communication of the compartments with one another and for effectively providing a leak-proof closure when the parts are applied.

25 A further object consists in providing the water bag with interchangeable closure means and a removable syringe connection whereby the bag may be readily used as a syringe or the like.

30 Other objects and advantages of the invention will become apparent from the following description when taken in conjunction with the accompanying claims and drawing.

35 Referring to the drawing in which are disclosed several preferred embodiments the invention may assume:

Figure 1 is a longitudinal cross sectional view of my improved water bag;

Figure 2 is a cross sectional view taken substantially along the line 2—2 of Figure 1;

Figure 3 is a sectional view taken substantially along the line 3—3 of Figure 1;

Figure 4 is a sectional view taken substantially along the line 4—4 of Figure 1;

45 Figure 5 is a view similar to Figure 3 showing a discharge nipple connected to the bag for the purpose of using the same as a syringe;

Figure 5a is a detail sectional view of a modified form of a syringe nipple which may be connected to the bag;

Figure 6 is a sectional view of a modified form of closure which may be associated with the bag.

Referring to the drawing in which like numerals indicate like parts in the several views, 55 10 designates the body of a water bag which may

be formed of soft, flexible, water-proof material such as rubber or the like, and which interiorly is provided with spaced partitions 11 which constitute separate compartments or chambers 12 for receiving the hot or cold liquid, and which are arranged to retain the same within a prescribed or restricted area of the bag. The partitions 11 may be integrally connected to the top 13 and the bottom 14 of the bag in order to constitute a one piece structure and may be made 10 of the same material as the bag. The bag 10 may be of any desired shape and size and has extending upwardly from the bottom 14 a tubular portion or member 15 of hard rubber, vulcanized or otherwise secured to the soft rubber of 15 the bag, so as to provide a filling and discharging passage 16. The member 15 has a reduced lower wall 17 provided with spaced circumferentially disposed openings 18 communicating with adjacent compartments 12 for conducting the liquid 20 from the passage 16 to the compartments. In other words, the passage 16 constitutes a common means for filling the compartments as well as for receiving the liquid from the compartments. The tubular portion 15 is preferably 25 positioned adjacent one end and medially of the width of the bag. The inner ends of the partitions 11 are preferably of hard rubber and are secured to the outer side of the tubular portion 15 between the openings 18, in order that the 30 compartments 12 may extend outwardly from the tubular portion 15 toward the sides of the bag. Thus, the entire area of the bag is divided into spaced elongated compartments in which the liquid may be confined.

Above the openings 18, the tubular portion 15 has a laterally disposed shoulder or offset portion 19 and an interiorly threaded enlarged flange or neck 20 which constitutes a filling mouth for introducing the liquid into the compartments 12 through the passage 16 and the spaced openings 18. The threaded neck 20 interchangeably receives either a long threaded closure or cap 21 (Figure 3) or a relatively short threaded closure 22 (Figure 4), depending upon 40 the use to which the bag is to be applied. The inner end of the reduced portion 17 is preferably threaded as at 23 for coacting with the threads on the neck to rigidly secure closure 21 45 to the bag.

The closure 21 has an enlarged smooth external portion 24 (Figure 3) and a reduced depending skirt 25 externally threaded as at 26, which are connected by an offset portion 27'. When the closure is applied to the bag, the smooth 50

portion 24 will be spaced from the threads of the neck 20 and the threads 26 of the skirt 25 will engage the threads 23, thus providing means to firmly but releasably secure the closure to the bag. At the same time, the skirt 25 will extend below the openings 18 to cut off communication between the compartments 12 and the central passage or opening 16 so that the liquid in the compartments will be retained therein and prevented from escaping from one compartment to another.

In order to provide a leak-proof connection when either the closure 21 or the closure 22 is applied to the bag, a gasket 27 may be positioned on the shoulder 19 to engage a portion of the closure, and thus preclude the liquid from escaping through the tubular member 15. The side of the bag adjacent the member 15 has an internally threaded discharge port 28 (Figure 3) 20 which registers with one of the openings 18 and is normally closed by the threaded plug 29.

When it is desired to use the bag 10 as a hot or cold water bottle, the closure is removed therefrom and liquid at the desired temperature is 25 initially introduced into the opening 16 of the tubular member 15 from where it is distributed into the compartments 12 through the openings 18. The closure 21 is then applied (Figure 3) so that the lower threaded portion thereof engages 30 the complementary threaded portion on the tubular member, and as the shoulder 27' is brought into engagement with the gasket 27, the latter is compressed and thus provides a tight seal for preventing the escape of the liquid through the 35 tubular member. The shoulder 27' also limits the inward movement of the closure. When the cap is properly applied, the skirt 25 cuts off communication between the compartments 12 and the opening 16 in the tubular member and also 40 closes communication of the compartments with one another. Thus, the liquid in each compartment is effectively retained therein and prevented from escaping from one compartment to another.

In the event the bag is desired to be used as 45 a syringe when the compartments are filled with water, it is merely necessary to first remove the plug 29 from the threaded opening 28 and substitute therefor the threaded nipple 30 of the syringe tube (Figure 5). The closure 21 is now 50 replaced by the cap 22 so that the liquid in the compartments 12 may escape into the central passage 16 through the openings 18 and discharge through the nipple 30 to the syringe. When the closure 22 is applied, the lower end thereof abuts 55 the gasket 27 to prevent the escape of liquid through the tubular member.

The end of the bag 10 opposite the tubular member 15 may be provided with an outwardly extending tab 32 having an opening 33 for constituting suspending means to support the bag on a nail or the like when the bag is used as a 60 syringe.

In the modified form of the invention illustrated in Figure 6, the tubular portion or mouth 34 of the bag is constructed in substantially the same manner as the member 15 previously described and has its lower annular wall 35 provided with spaced circumferentially disposed openings 36, each of which communicates with an aligned 65 compartment 37 similar in construction to the compartments 12. The wall 35 is connected to an enlarged interiorly threaded neck 38 by an offset portion or shoulder 39, but is not interiorly threaded as in the form previously described. 70 Associated with the tubular member is a remov-

able closure 40 which has an enlarged threaded portion 41 arranged to engage the threads of the neck 38. The closure 40 is also provided with a reduced depending skirt 42, spaced from the adjacent wall 35 of the tubular member. The skirt 42 is arranged to receive a tapered annular band or gasket 43 of substantially the same length as the length of the outer portion of the skirt, so that upon the cap being threaded to the tubular portion 34, the band 43 will be moved downwardly 10 into wedging engagement between the wall 35 and the skirt 42 to close the openings 36, and thus provide a tight seal for preventing the escape of liquid from the compartments 37 into and through the tubular member. One of the 15 openings in the tubular member such as 44 has its wall threaded to receive either the plug 29 or the syringe nipple 30 so that the bag may be interchangeably used as a hot or cold water bag 20 or as a syringe.

The tubular member in each form of the invention shown and the closures associated therewith, are preferably made of hard rubber composition so as permanently to maintain their pre-formed shapes, but if desired, these parts may 25 be formed of suitable metal.

Thus, it will be seen that the present invention provides a water bag having separate compartments for receiving the heating or cooling liquid, and in which means are provided in the form of 30 interchangeable closures for either closing communication between the various compartments or permitting the discharge of the liquid therefrom. When the bag is used as a hot water bottle, the closure applied thereto will cut 35 off communication of the compartments from one another so that the bag may be applied to the affected portion of the body without danger of the liquid escaping to remote portions of the bag. Moreover, the liquid in each compartment 40 will be effectively retained therein so as to localize its heating or cooling area irrespective of the position or shape the bag may assume.

Further, when it is desired to convert the bag 45 into a syringe, it is merely necessary to substitute for the closure plug 29, the nipple 30 and to remove the cap 21 and apply the cap 22 so that the liquid in the several compartments may discharge into the central passage of the tubular member and through the nipple 30 to the syringe. 50

As shown in Figure 5, the discharge opening in the nipple 30 is of such a size as to permit the ordinary flush flow of the liquid from the bag 10 into the syringe tube. In certain instances, it is desirable that the water discharge slowly and 55 at a predetermined rate through the syringe tube. Accordingly, there may be provided a threaded nipple 45 as shown in Figure 5a, which may be readily substituted for the nipple 30 to connect the syringe with the bag 10. As shown, 60 the nipple 45 has a restricted opening or discharge passage 46 of such a size that the water in the bag flows through the nipple 45 at the rate of about one quart an hour. Manifestly, the size of the opening 46 may be varied as conditions 65 warrant. Moreover, instead of providing a separate nipple to control the flush flow to the syringe, other means such as a washer or the like may be associated with the nipple for this purpose. 70

It is to be understood that the forms of the invention shown and described are merely illustrative of preferred embodiments and that such changes may be made as fall within the purview of one skilled in the art without departing from 75

the spirit of the invention and the scope of the appended claims.

I claim:

1. A water bag of the class described including a flexible hollow body having an internally threaded tubular member extending upwardly through the body and provided with a filling passage, spaced partitions extending from said tubular member to the sides of the bag to separate the same into spaced compartments, said tubular member having circumferentially disposed openings between the partitions for communicating the compartments with said passage, and an externally threaded closure removably connected to said member and having a depending skirt for closing communication between said compartments and said passage when the closure is applied to the bag.

15 applied to the bag.

2. A water bag of the class described including
20 a flexible hollow body having a tubular member
extending upwardly through the body and pro-
vided with a centrally disposed filling and dis-
charging passage, spaced partitions extending
outwardly from said tubular member to the sides
25 of the bag to separate the same into spaced com-
partments, said tubular member having its lower
wall internally threaded and provided with cir-
cumferentially disposed spaced openings between
the partitions for communicating the compart-
30 ments with said passage, said tubular member
above said openings having an offset shoulder ter-
minating in an enlarged neck, and an externally
threaded closure removably connected to said
member.

35 3. A water bag of the class described including a flexible hollow body having a tubular member extending upwardly through the body and provided with a centrally disposed filling and discharging passage, spaced partitions extending
40 from said tubular member to the outer sides of the bag to separate the same into spaced compartments, said tubular member having its lower wall internally threaded and provided with circumferentially disposed spaced openings between
45 the partitions for communicating the compartments with said passage, said tubular member above said openings having an offset shoulder terminating in an enlarged neck, and a removable closure having a reduced depending externally threaded skirt engaging the lower wall of the tubular portion to close communication between said compartments and said passage when the closure is applied to the tubular
50 member.

4. A water bag of the class described including a flexible hollow body having a tubular member extending upwardly through the body and provided with a centrally disposed filling and discharging passage, spaced partitions extending outwardly from said tubular member to the sides of the bag to separate the same into spaced compartments, said tubular member having its lower wall internally threaded and provided with circumferentially disposed spaced openings between the partitions for communicating the compartments with said passage, said tubular member above said openings having an offset shoulder terminating in an enlarged internally threaded neck, and a plurality of closures arranged for interchangeable connection with the threaded portions of said tubular member. 5 10 15

5. A water bag of the class described including a flexible hollow body having a tubular member extending upwardly through the body and provided with a filling passage, spaced partitions extending from said member to the sides of the body to separate the same into spaced compartments, said member having its lower wall internally threaded and provided with spaced openings for communicating the compartments with said passage, said member above said openings having an outwardly extending shoulder terminating in an enlarged internally threaded neck, said bag having a discharge port communicating with said passage, a removable plug for closing said port, and a cap for closing said neck. 20 25 30

6. A water bag of the class described including a flexible hollow body having a tubular member extending upwardly through the body and provided with a central filling passage, spaced partitions extending from said tubular member to the sides of the body to separate the same into spaced compartments, the lower wall of said tubular member being internally threaded and provided with spaced openings between the partitions for communicating the compartments with said passage, said tubular member above said openings having an outwardly extending shoulder terminating in an enlarged internally threaded neck, said bag having a discharge port communicating with said passage, a removable plug for closing said port, interchangeable threaded closures arranged to be connected to said tubular member, and means when the plug is removed for attaching to said port a syringe nipple for discharging the liquid in the bag through said passage into and through said nipple.

MAE H. BROWN. 55
